UNITED STATES PATENT OFFICE.

WILLIAM H. MILLER, OF HILLSBORO, ILLINOIS.

PUZZLE.

Application filed August 18, 1920. Serial No. 404,401.

To all whom it may concern:

Be it known that I, WILLIAM H. MILLER, a citizen of the United States, and residing at Hillsboro, Illinois, have invented the new and useful Improvement in Puzzles, of which the following is a specification.

This invention relates to puzzles having particular reference to number puzzles wherein the solution of the puzzle depends upon certain arrangements of numbers.

One of the objects of this invention is to provide a puzzle which is more or less difficult of solution, which shall hold the interest of the one attempting to solve it and which shall be capable of considerable variation.

Further objects will appear from the detail description taken in connection with the accompanying drawing in which:

Figure 1 shows a top view of the puzzle board with the number plugs removed;

Figure 2 shows the puzzle board with the number plugs in place to show one solution of the puzzle;

Figure 3 shows sixteen different cover cards for this puzzle;

Figure 4 shows one of the cover cards applied to the puzzle board;

Figure 5 shows the same cover card applied to the same puzzle board in a different position.

Figure 6 shows the same cover card applied to the same puzzle board but in inverted position from that of Figure 4;

Figure 7 shows the same cover card applied to the same puzzle board in inverted position from that shown in Figure 5;

Figure 8 shows the arrangement of the puzzle board and the cover cards packed in a container;

Figure 9 shows a puzzle board of modified construction;

Figure 10 shows a partial section taken on line 10—10 of Figure 9;

Figure 11 shows a number plug removed from the board;

Figure 12 shows a key for the puzzle; and

Figures 13, 14 and 15 show modified arrangements of said key.

Figures 16, 17, 18 and 19 show another embodiment.

Referring now to the accompanying drawings, 10 designates a box or container in which the puzzle may be packed and stored. The puzzle proper comprises a puzzle board 12 which may be of wood, card board or any other suitable material, and which may be provided with perforations or sockets 13 adapted to receive and retain number plugs 14. Each of the plugs 14 may have a number printed, written or otherwise impressed thereon or some of them may be left blank. These plugs may be constructed to fit the sockets 13, so that when inserted therein, they will be frictionally retained. All of the plugs may be loose or removable from the board 12, or some may be fixed and some loose. The sockets 13 are preferably arranged in a rectangular pattern, that is so as to form vertical rows of numbers A, B, C, D, and horizontal rows E, F, G, H, although this arrangement is not essential, as numerous other patterns may be worked out.

The numerals 16 to 31 inclusive designate cover cards which may be of paper, card board or any other suitable material, preferably of the same size and shape as the puzzle board 12, though this is not essential, and adapted to be superimposed thereon so as to register therewith. Each cover card has a series of perforations 1, 2, 3, and 4, each perforation being so situated that when the cover card is registered with the puzzle board, one of the plugs will be disclosed through said perforation in the cover card. The perforations 1, 2, 3 and 4 may be arranged in a number of different patterns as shown in Figure 3 and the solution of the puzzle consists in so arranging the number plugs 14 in the puzzle board 12 that when any of the cards 16 to 31 inclusive is superimposed on said board, the sum of the numbers disclosed through the perforations 1, 2,

3 and 4, will be the same in whatever position the cover card is placed in proper registry with the board. Any of the cards shown in Figure 3 may be placed upon the board shown in Figure 2 in any position and either side up, and the sum of the numbers disclosed through the perforations will always be the same, namely 34 in the present case. This is clearly shown in Figures 4, 5, 6 and 7 in which the card 17 is shown placed upon the board shown in Figure 2 in four out of a possible eight positions. While only four positions are shown, all eight positions will give the same result. Figures 9 and 10 show a slightly modified construction of the puzzle board 12. In this construction the puzzle board 32 consists of two sheets of card board or other suitable material mounted one upon the other, the upper sheet having perforations 33 adapted to receive the number plugs 14, and the lower sheet having somewhat smaller perforations 34 arranged to register with the perforations 33 of the upper sheet so as to form a shoulder 35 adapted to support the plug 14. The hole 34 allows for the insertion of the finger to remove the plug.

The arrangement of numbers shown in Figure 2 is, of course, not the only arrangement that can be used for a puzzle according to this invention. Numerous other arrangements are available. Such arrangements are in fact so numerous that it is convenient to have a key whereby a new number set may be obtained at any time. Such a key is shown in Figures 12 to 15 inclusive. This key comprises a board similar to the puzzle board which may be provided with a set of symbols in place of numbers arranged in a pattern similar to that of the puzzle board. In the present instance, the letters of the alphabet have been used as symbols. This board may be sub-divided into a number of sections, in the present instance, four quarter sections 40 to 43 inclusive. The quarter sections may be provided with finger notches 44 for convenience in manipulation.

It will be seen that the letters in Figure 12 taken in alphabetical order are arranged in the same pattern as the numbers in Figure 2 taken in numerical order. In other words, by substituting, in Figure 2, A for 1, B for 2, C for 3, etc., in alphabetical and numerical order respectively, the arrangement of Figure 12 is obtained. The arrangement of Figure 2 can be obtained from the arrangement of Figure 12 by reversing this process. Similarly, by substituting in Figure 12 any other set of consecutive numbers, maintaining, of course, the correspondence of alphabetical and numerical order as pointed out above, a new number set will be obtained, which will fulfill the requirements of this invention as pointed out above. The numbers substituted need not, however, be in

consecutive numerical order, but number sets may be obtained by a process to be described hereinafter, which when applied to the key shown in Figures 12 to 15 inclusive, or any of the other keys to be described hereinafter, 70 will produce a number pattern which will fulfill the requirements of this puzzle.

With any given number set applied to the key of Figure 12, a number of different number patterns may be obtained by manipulation of said key. If each of the quarter sections blocks 40, 41, 42 and 43 is rotated individually in the same direction through ninety degrees from its position in Figure 12, as indicated by the arrows in that figure, 75 a second pattern will be obtained as shown in Figure 13. This pattern will also fulfill the requirements of the puzzle. This operation may be repeated and after rotation will produce a new pattern. The fourth pattern so found is shown in Figure 14.

If the above rotation be again performed on Figure 14, the original pattern of Figure 12 will be obtained. If, however, instead of repeating said rotation, the two lower blocks of Figure 14 be transposed so as to lie above the two upper blocks as indicated by the arrows in that figure, a new pattern will be obtained as shown in Figure 15. (The two right hand blocks may be interchanged with the left hand blocks just as well.) Starting with the arrangement of Figure 15, the rotation process can again be performed three times, obtaining a new pattern each time. Thus from the key of Figure 12, a total of 90 eight different patterns may be obtained. 95

If we start with other patterns than those shown in Figure 12 by using the same set of symbols, still other number patterns may be obtained from the same number set, which will fulfill the requirements of the puzzle. A number of key patterns which may be used are shown in the following tabulation in which the letters given in the first line correspond to those of figure 12 and each succeeding line gives a new pattern which may be applied to the key by substituting each letter in that line for the letter above it in column in the first line. 100 105 110 115

A	B	C	D	E	F	G	H	I	J	K	L	M	N	O	P
A	B	C	D	I	J	K	L	E	F	G	H	M	N	O	P
A	C	B	D	E	G	F	H	I	K	J	L	M	O	N	P
A	C	B	D	I	K	J	L	E	G	F	H	M	O	N	P

From each of these, eight patterns may be obtained by the rotation process described above. It will be seen that by this process a large number of different number patterns may be obtained from the same number set. 125

An enormous number of different number sets may be obtained which when applied to the key described above will fulfill the conditions of the puzzle. A method of obtaining such number sets is illustrated in the follow- 130

ing tabulation. In the first line are the letters or other symbols corresponding to the key of Figure 12. Each succeeding line re-

resents a new number set which may be applied to the key substituting each number in that set for the letter above it in column.

A	B	C	D	E	F	G	H	I	J	K	L	M	N	O	P
(X)	(W)	(X)	(Y)	(X)	(W)	(X)	(Z)	(X)	(W)	(X)	(Y)	(X)	(W)	(X)	
1	2	3	4	5	6	7	8	9	10	11	12	13	14	15	16
-9	-8	-7	-6	-5	-4	-3	-2	-2	-1	0	1	2	3	4	5
14	13	6	5	10	9	2	1	16	15	8	7	12	11	4	3
-3	-2	-1	0	13	14	15	16	16	17	18	19	32	33	34	35

The letters W, X, Y and Z placed between successive terms of the above series of numbers represent the algebraic difference be-

10 between successive terms. Wherever the same letter appears, said difference must be the same. These differences may have any value, but such value must always be the same for the same letter during a series. Thus,

15 In the first series

$$\begin{aligned} W &= 1 \\ X &= 1 \\ Y &= 1 \\ Z &= 1 \end{aligned}$$

In the second series

$$\begin{aligned} W &= 1 \\ X &= 1 \\ Y &= 1 \\ Z &= 0 \end{aligned}$$

20 In the third series

$$\begin{aligned} W &= -7 \\ X &= -1 \\ Y &= 5 \\ Z &= 15 \end{aligned}$$

In the fourth series

$$\begin{aligned} W &= 1 \\ X &= 1 \\ Y &= 13 \\ Z &= 0 \end{aligned}$$

25 There are various ways in which this puzzle may be presented for solution. The puzzle board with the number plugs removed or displaced from their proper pattern may be presented together with one or more cover cards, to be solved by finding a pattern which will fulfill the requirements; or more than one solution may be demanded; or one or more solutions may be demanded using all the number plugs and an additional solution with one or more number plugs omitted from the pattern; or certain numbers may be permanently located in the pattern and one or more solutions required.

30 The following is an illustration of two solutions which may be obtained with the number set consisting of the numbers 1 to 16, in which the number 8 has been omitted

from the pattern, and the numbers 3, 13, 16 and the blank have been fixed in the pattern.

14	6	3	9	15	10	3	4
12	15	5		7	14	11	65
11	1	4	16	5	2	9	16
7	13	10	2	12	13	6	1

35 It will be noted that in the second and fourth series of numbers given above, one of the numbers is zero. This, of course, is the same as if no number at all were given, or a blank space left on the board. This means that when the puzzle is presented for solution the zero may be replaced by some arbitrary number which will prevent a successful solution until discarded. In such a case, of course, instructions should be given to discard or replace one number. It will be obvious also that any other number than zero can be treated in the same way.

40 Various modifications of this puzzle are possible. For instance, two or more puzzle boards may be combined. When four are combined making one puzzle board consisting of four boards as described above, in the form of a square, cover cards can be provided having their perforations arranged as combinations of the arrangements shown in Figure 3, so that they may be applied to the puzzle board in any position with a similar result as is obtained with the single board.

45 A way of combining four puzzle boards in such a way to make the puzzle more difficult of solution, is shown in Figures 16 to 19. Figure 16 represents a puzzle board having in all sixty-four spaces for numbers, arranged in a square with eight spaces on each side. For the sake of clearness in nomenclature, we may consider this board as divided into four "quadrants," each "quadrant" being divided into four "quarter sections" and each quarter section into four "spaces." The 50 quarter sections of this board are lettered, each at its center, with letters placed to correspond with a puzzle board having sixteen number spaces as described above. Each of the "quarter sections" of the present board corresponds to a single number 55 space" of the sixteen space board, as previously described, and the letters are placed on said sections according to the original key pattern, as described for such a board.

The "spaces" of each quarter section are lettered with the same letters as applied to that section and in addition, are numbered to indicate their relative positions in that 5 quarter section. Thus, the quarter section A, has four spaces A 1, A 2, A 3, and A 4, and similarly for all the other quarter sections. The numbering of the spaces of each 10 quarter section may be determined as follows:

First, each space is given a letter corresponding to the letter of its quarter section. Next, a pattern is selected such as shown in Figure 17, which may be superimposed upon one quadrant of the board so as to disclose one space of each quarter section of that quadrant. In each space so disclosed, the number 1 is added to the symbol for that space, so that, for instance, 15 the first spaces of the first quadrant will bear the symbols A 1, N 1, K 1, and H 1. The pattern may now be turned about the vertical center line of the board as an axis, (Figure 19) so as to lie upon the second 20 quadrant of the board. It will now disclose one space of each quarter section as before. The spaces so disclosed are numbered 1, as before. The pattern may now be turned about the horizontal center line of the board 25 as an axis so as to lie upon the third quadrant, and again the spaces disclosed are each numbered 1. The process is again repeated by turning the pattern about the vertical center line as an axis so as to lie upon 30 the fourth quadrant, and the disclosed spaces are again numbered 1.

We now have sixteen spaces bearing symbols A 1, B 1, C 1, etc., up to P 1, and located in quarter sections arranged relatively 40 to each other to correspond with the original key pattern. These numbered sections are furthermore located symmetrically with respect to the center of the board.

If the pattern is now turned about the 45 horizontal center line of the board as an axis from its last position in the fourth quadrant, it will regain its first position in the first quadrant. The pattern may now be rotated about an axis through its center and perpendicular to the plane of the 50 paper to a new position over the first quadrant and a new set of four spaces will be disclosed. These four spaces may now be numbered 2, so as to complete the 55 symbols A 2, N 2, K 2 and H 2. The process of rotating the pattern successively about each of the center lines of the board, as described before, may now be repeated so as to complete the symbols of a second set of spaces A 2, B 2, C 2, etc., up to P. 2. We now have a second set of symbols placed in the quarter sections according to the original key pattern.

By continuing this process, proper symbols may be placed in all of the spaces of

the board, and we will have four complete sets of symbols, each arranged on the board in the quarter sections according to the original key pattern. The pattern used in producing this arrangement may be varied 70 by omitting some of the perforations, or shifting their location, provided that by so doing, no space in a quadrant is disclosed in more than one position of the pattern.

The pattern shown in Figure 16 may be 75 varied by rotating all of the quarter sections as described for Figures 12 to 15 inclusive. The numbers to be applied to the spaces are obtained by taking any four number sets, obtained as previously described, and applying one to each of the symbol sets A 1, B 1, etc., A. 2, B 2, etc., A 3, B 3, etc., A 4, B 4, etc. Such number sets must, however, have the same values of W, X, Y and Z and in addition, the difference between P 1 and A 2 must be equal to the difference between P 3 and A 4.

It will be seen that a puzzle is, therefore, produced which, when certain numbers are left out, will be very difficult of solution.

Another type of cover card (Fig. 19) may be produced by arranging the perforations so as to disclose numbers similarly located in each of the four quadrants. By this is meant, an arrangement which would disclose, for instance, 1, 2 or 3 adjacent numbers in the upper left hand corner of each quadrant.

It is obvious that various changes may be made in the details of construction without departing from the spirit of this invention; it is, therefore, to be understood that this invention is not to be limited to the specific details shown and described.

Having thus described this invention, what is claimed is:

1. A puzzle comprising a set of numbers to be arranged in a pattern, and a second fixed pattern adapted for superposition thereon and individually defining certain number locations such that an arithmetical operation performed upon the numbers common to both patterns will yield a constant result irrespective of the relative positions of said patterns.

2. A puzzle comprising a set of numbers to be arranged in a main pattern, and a plurality of auxiliary patterns adapted for superposition thereon and each individually defining certain number locations, such that an arithmetical operation performed upon the numbers common to said main pattern and any of said auxiliary patterns will yield a constant result for all of said auxiliary patterns.

3. A puzzle comprising a set of numbers to be arranged in a main pattern, and a plurality of auxiliary patterns adapted for superposition thereon and each individually defining certain number locations, such that

- an arithmetical operation performed upon the numbers common to said main pattern and any of said auxiliary patterns will yield a constant result for all of said auxiliary patterns, and for any relative position of said main and auxiliary patterns. 5 70
4. A puzzle comprising a set of numbers to be arranged in a plurality of patterns, and a second fixed pattern adapted for superposition on any of said first patterns so as to individually define certain number locations, such that an arithmetical operation performed on the numbers common to both patterns will yield a constant result for all of said first patterns. 10 75
5. A puzzle comprising a set of numbers to be arranged in a plurality of patterns, and a second fixed pattern adapted for super-position on any of said first patterns so as to individually define certain number locations, such that an arithmetical operation performed on the numbers common to both patterns will yield a constant result for all of said first patterns irrespective 15 80

- 65 130
- an auxiliary pattern being such that one or more of said numbers may be discarded and the remaining numbers rearranged into a new pattern which will satisfy the same requirements. 70
10. A puzzle comprising a set of numbers to be arranged in a main pattern, and a plurality of auxiliary patterns adapted for super-position thereon, such that an arithmetical operation performed upon the numbers common to said main pattern and any of said auxiliary patterns will yield a constant result for all of said auxiliary patterns and for any relative position of said main and auxiliary patterns, said main pattern being such that one or more of said numbers may be discarded and the remaining numbers rearranged into a new pattern which will satisfy the same requirements. 75
11. A puzzle comprising a set of numbers to be arranged in a plurality of patterns, and a second pattern adapted for super-position on any of said first patterns, such that an arithmetical operation performed on the numbers common to both patterns will yield a constant result for all of said first patterns, said first patterns each being such that one or more of said numbers may be discarded and the remaining numbers rearranged into a new pattern which will satisfy the same requirements. 80
12. A puzzle comprising a set of numbers to be arranged in a plurality of patterns, and a second pattern adapted for super-position on any of said first patterns, such that an arithmetical operation performed on the numbers common to both patterns will yield a constant result for all of said first patterns irrespective of the relative positions of said first and second patterns, said main pattern being such that one or more of said numbers may be discarded and the remaining numbers rearranged into a new pattern which will satisfy the same requirements. 85
13. A puzzle comprising a set of numbers to be arranged in a plurality of patterns, a plurality of second patterns adapted for super-position on said first patterns, such that an arithmetical operation performed on the numbers common to any of said first patterns and any of said second patterns will yield a constant result, said first patterns each being such that one or more of said numbers may be discarded and the remaining numbers rearranged into a new pattern which will satisfy the same requirements. 90
14. A puzzle comprising a set of numbers to be arranged in a plurality of patterns, a plurality of second patterns adapted for super-position on said first patterns, such that an arithmetical operation performed on the numbers common to any of said first

patterns and any of said second patterns will yield a constant result, irrespective of the relative positions of said first and second patterns said first patterns each being 5 such that one or more of said numbers may be discarded and the remaining numbers rearranged into a new pattern which will satisfy the same requirements.

15. A puzzle comprising a set of numbers 10 to be arranged in a pattern, and a second pattern adapted for superposition thereon, said first pattern being such that one or more of said numbers may be discarded and thereafter an arithmetical operation performed on the numbers common to both said superposed patterns will yield a constant result irrespective of the relative positions of said pattern.

16. A puzzle comprising a set of numbers 20 to be arranged in a pattern, and a second pattern adapted for superposition thereon, said first pattern being such that one or more of said numbers may be replaced by another number and thereafter an arithmetical operation performed on the numbers common to both said superposed patterns will yield a constant result irrespective of the relative positions of said patterns.

17. A key for a number puzzle, comprising, 30 a set of symbols arranged in a pattern adapted for finding number sets for the puzzle by substitution of numbers for said symbols, said pattern being arranged in subdivisions adapted by rearrangement to form 35 new number sets.

18. A key for a number puzzle, comprising, 40 a set of blocks each having a set of symbols and adapted for juxtaposition to form a pattern wherefrom a number set may be obtained by substitution of numbers for said symbols, and means for rearranging said blocks to form new number sets.

19. A puzzle comprising a set of numbers 45 to be arranged in a pattern, and a second pattern adapted for super-position thereon such that an arithmetical operation performed upon the numbers common to both patterns will yield a constant result irrespective of the relative positions of said patterns, said first pattern being adapted to have certain of its numbers fixed in relative position therein, and the rest rearranged to form a new pattern adapted to fulfill the same requirements.

20. A puzzle comprising a set of numbers 55 to be arranged in a main pattern, and a plurality of auxiliary patterns adapted for super-position thereon, such that an arithmetical operation performed upon the numbers common to said main pattern and any of said auxiliary patterns will yield a constant result for all of said auxiliary patterns, said main pattern being adapted to have certain of its numbers fixed in relative position 60 therein, and the rest rearranged to form a

new pattern adapted to fulfill the same requirements.

21. A puzzle comprising a set of numbers 70 to be arranged in a main pattern, and a plurality of auxiliary patterns adapted for super-position thereon, such that an arithmetical operation performed upon the numbers common to said main pattern and any of said auxiliary patterns will yield a constant result for all of said auxiliary patterns and for any relative position of said main and auxiliary patterns, said main pattern being adapted to have certain of its numbers fixed in relative position therein, and the rest rearranged to form a new pattern adapted to 80 fulfill the same requirements.

22. A puzzle comprising a plurality of numbered members, means for supporting said numbered members, and perforated members adapted for engagement over said numbered members to disclose certain of said numbered members to produce when added together a predetermined sum regardless of the position of the perforated members upon said numbered members.

23. A puzzle comprising a supporting member, numbered members adapted for various arrangements upon said supporting member, and perforated sheets adapted for engagement over said numbered members to 95 disclose certain of said numbered members to produce a predetermined sum when added together regardless of the position of the perforated sheets.

24. A puzzle comprising a supporting 100 member, perforated discs adapted for arrangement upon said supporting member, and reversible perforated sheets adapted for engagement over the numbered discs to disclose certain of said discs for producing 105 when adding together a total predetermined sum when said perforated sheets are in various positions upon said numbered discs.

25. A puzzle comprising a supporting member, a set of numbered discs adapted for 110 various arrangements upon said supporting member, and numbered sheets adapted for engagement in various positions upon said perforated discs when the latter are in their different arrangements to disclose certain of said discs to produce a predetermined sum when the numbers on the discs are added together, the same total sum being produced by the numbers on the disclosed disc when the perforated sheets are in their different 115 positions over said numbered discs.

26. A puzzle comprising a board, blocks 120 removably positioned upon the board and numbered upon their opposite faces, and cards having openings formed therein for 125 certain of the blocks when the cards are placed over the boards, the cards having the same number of openings but no two cards having the openings cut in the same relative arrangement.

27. A puzzle comprising a playing board, numbered blocks removably positioned upon said board, and cards each provided with a plurality of openings disclosing a predetermined number of numbered blocks when the cards are placed over the board, these blocks being so arranged upon the board that the sum of the numbers disclosed through the openings will at all times have the same result.

28. A puzzle comprising a board, a plurality of blocks removably positioned upon said board and having numbers provided thereon, and a card having a plurality of openings formed therein, the openings being so arranged that added numbers of the blocks showing through the openings will produce the same amount when added, regardless of the position of the cards upon the playing board.

29. A puzzle comprising a board having sockets formed therein, blocks fitting into the sockets and removable therefrom and having numbers provided on their upper faces, and a card having openings formed therein for disclosing certain of the blocks when the cards are placed over the board, the numbers disclosed through the openings adding to produce the same result without regard to positioning the cards when the blocks are properly placed upon the board.

30. A puzzle comprising a board, blocks positioned upon the board and removable therefrom and having numbers provided upon their upper faces, and cards each hav-

ing a plurality of openings formed therein for showing certain of the blocks through the openings with the numbers disclosed at all times when added producing the same result without regard to the cards selected or the position of the card upon the board when the blocks are properly arranged upon the board.

31. A puzzle comprising a board, blocks removably positioned upon the board and numbered to correspond to the number of blocks on one face, the cards having openings formed therein for disclosing certain of the blocks when the cards are placed over the board, the cards having the same number of openings but no two cards having openings cut in the same relative arrangement.

32. A puzzle comprising a board, numbered disks arranged on said board so that a predetermined number of the disks will produce a predetermined sum when the numbers thereof are added together, said disks being arranged so that various sets or rows thereof may total the same predetermined sum when added together, and perforated sheets adapted for engagement over said blocks to disclose said sets and rows of numbered disks when the cards are placed in various positions over said disks, each perforated sheet having the perforations arranged differently and adapted for a number of various positions over said disks.

In testimony whereof I affix my signature this 25th day of June, 1920.

WILLIAM H. MILLER.
